LIGHT-DEFLECTING MEANS FOR HEADLIGHTS.

1,399,143.

Specification of Letters Patent.

Patented Dec. 6, 1921.

Application filed October 5, 1920. Serial No. 414,739.

To all whom it may concern:

Be it known that I, DANIEL F. MORIARTY, a citizen of the United States of America, and a resident of Holyoke, in the county of 5 Hampden and State of Massachusetts, have invented a certain new and useful Light-Deflecting Means for Headlights, of which the following is a specification.

My invention relates to improvements in 10 means to deflect the light from headlights used on automobiles and other road vehicles, and consists essentially of a translucent body which is provided on the back side with a series or plurality of certain peculiarly constructed, integral louvers, said body being receivable in a lamp casing and taking the place of the ordinary lens therein, all as hereinafter set forth.

This means or device is usually made of 20 glass, and some or all of the louvers thereof are rendered opaque on their upper surfaces by means of paint, enamel, or other suitable material applied thereto, and it has been found that it is also desirable to render the 25 under side of the bottom louvers opaque in the same manner or by the same means.

The body portion of the device is of a 30 shape to fit into the front end of the lamp casing which is provided with said device, such end being annular as a rule, so that said body has the general form of a disk.

The primary object of my invention is to 35 provide light-controlling means, for lamps in the class specified above, which is simple and comparatively inexpensive in construction, a unitary device and compact, and highly practicable and efficient, and whereby the glare of the most powerful headlight is cut down or entirely eliminated, and this 40 without losing an excessive or undue amount of the light, but, on the contrary, utilizing the same to the best advantage for illuminating the path ahead of the lamp which is equipped with the aforesaid means. With 45 this device the proper range of projection and the required height of the rays of light from the headlight are obtained, and said rays are concentrated and freely distributed laterally so that their direction 50 ahead of the source of light, that is to say, the lamp proper, is uniform. In other words, the rays of light with relation to an observer at a predetermined point in advance of and above the longitudinal or hori-

zontal, forwardly and rearwardly extending 55 axis of said lamp are substantially dimmed or entirely cut out, while the maximum amount of lighting efficiency produced by rays directed downwardly toward the roadway ahead of the vehicle for the desired distance is obtained.

Another object is to provide a device which obviates the necessity of applying to the exterior of the headlight any dimming means.

Other objects and advantages will appear 65 in the course of the following description.

I attain the objects and secure the advantages of my invention by the means illustrated in the accompanying drawings, in which—

Figure 1 is a rear elevation of a device 70 which embodies a practical form of my invention; Fig. 2, a vertical section through said device, taken on lines 2—2, looking in the direction of the associated arrow, in Fig. 1, and, Fig. 3, a transverse section through said device, on lines 3—3, Fig. 1.

Similar reference characters designate similar parts throughout the several views.

The device consists of a body 1 which is 80 in the shape of a disk, or such other shape as may be required in order to fit within the front end of a headlight casing, and a series of horizontal projections or louvers 4 on the back side of said body, there being nine such 85 louvers in the present case, although such number would vary in devices of different sizes and designed to produce different results. The body 1 has approximately flat, parallel sides, and the rear or inner edges of 90 the louvers 4 are all in the same plane with each other, which plane is parallel with the sides of said body. Each louver is generally wedge-shaped in cross section, but preferably has a blunt rear or inner edge instead 95 of being sharp at such edge like an ordinary wedge. When the device is in position in a lamp casing the rear or inner edges of the louvers are adjacent to the source of light.

The body 1 and its louvers are made in 100 one piece, being molded preferably and probably from necessity of glass. This glass must, of course, be transparent or in any event translucent. The upper sides of all of the louvers, with the possible exception of two or three of those at the bottom, and the underside of the bottom louver are 105 treated with some opaque substance, usually

a black or dark paint, as indicated at 5 in Fig. 2, so that no light can pass through the parts or surfaces thus treated. The ends of the louvers are rounded, as represented at 6, in order that there shall be no sharp corners, and to strengthen the louvers and increase their efficiency.

The louvers 4 are inclined relative to each other, with the exception of the bottom 10 louver the upper surface of which is approximately horizontal in both directions, such inclination being upwardly and inwardly or rearwardly. The relative angles of inclination of the louvers, commencing 15 with the uppermost louver, decrease gradually in sequence from said uppermost louver downwardly to the lowermost louver, said uppermost louver, therefore, having the greatest angle of inclination with relation 20 to the aforesaid axis of the lamp. The louvers below said axis permit the greatest number of horizontal rays of light to pass forwardly, due to their angular relation to said axis, while the angular relation of the 25 louvers above the axis is such as gradually to cause to diminish upwardly the quantity of rays passing horizontally forwardly from the source of light and the reflector for said source. Thus the length of the rays projected forwardly from the source of light is determined and said rays are caused to strike the ground at a given point in advance of such source by the angles of the louvers, all of which is predetermined.

30 When the device is viewed from a given point in front of the lamp and above the aforesaid axis thereof, the several louvers form a substantially total blind which obliterates rays of light from said lamp, and 35 so prevents the glare of the light from blinding the observer. Thus it is seen that at and above a given point of elevation the louvers act as complete blinds, shutting out the projecting rays; yet the desired and 40 maximum quantity of light is cast forwardly and directed downwardly at the desired angle and to the point ahead of the source of light, by the angularly disposed louvers, which collect and condense the rays directed 45 50 55

straight forwardly from the headlight, and also permit of the passage angularly or laterally of rays to produce or provide the desired illumination laterally with respect to the axis of the headlight to which reference has been hereinbefore made.

It is now clear that this device affords a simple, practicable, and substantial device, which may be readily mounted within a headlight casing, and reflects and distributes

the light to the best advantage and in the 60 most efficient manner.

In no case does the inner or rear edge of the upper surface of any intermediate louver project above a horizontal plane which intersects the angle between the under 65 side of the louver above and the contiguous side of the body 1, and even in the case of the top louver and the one immediately below the same, such edge of the upper surface of the latter is in a horizontal plane 70 which is little if any above the center of the distance between the junction of the said two louvers or of their adjacent surfaces with the body 1.

The opaque coating 5 on the tops or upper 75 sides of the nine louvers 4, or on any less number of the same, prevents the light from passing through such surfaces, but the rays of light are permitted to pass through such louvers and the body 1 at and below the 80 junctions of said coated or treated surfaces with said body. Practically no light passes through the bottom louver, because said louver is treated to render it opaque on both the upper and under surfaces.

85 The source of light or illuminating medium, such as an electric-light, is not herein shown, but in practice is situated behind the light deflecting means, with the horizontal or longitudinal axis of said electric-light approximately in line with the horizontal or transverse axis of said means.

90 Some change may be made in the shape and size, and in the arrangement, especially relative to the pitch as well as to the number 95 of the louvers, of the parts of this device, without departing from the spirit of my invention, or exceeding the scope of what is claimed.

95 100 What I claim as my invention, and desire to secure by Letters Patent, is—

As an improved article of manufacture, a device, of the class described, comprising a body and a plurality of approximately wedge-shaped louvers extending with varying inclinations upwardly and rearwardly from the back side thereof, said body and louvers being integral and intrinsically translucent, and the rear edges of said louvers being in a common plane which is 110 parallel with said body, and opaque material on certain of the major surfaces of said louvers.

DANIEL F. MORIARTY. [L.S.]
